UNITED STATES PATENT OFFICE.

ELENORA NEUMANN, OF NEW YORK, N. Y., ASSIGNOR OF ONE-HALF TO ARNOLD ZUKOR, OF NEW YORK, N. Y.

NURSING-BOTTLE HOLDER FOR BABY-CARRIAGES.

1,030,744.

Specification of Letters Patent. Patented June 25, 1912.

Application filed March 12, 1912. Serial No. 683,362.

To all whom it may concern:

Be it known that I, ELENORA NEUMANN, a subject of the King of Hungary, and resident of the city of New York, in the county 5 of New York and State of New York, have invented certain new and useful Improvements in Nursing-Bottle Holders for Baby-Carriages, of which the following is a specification.

10 The present invention relates to a nursing bottle-holder, and more particularly to one which is specially useful in connection with baby-carriages or go-carts.

One of the objects of the invention is to 15 provide a device of this character which is simple in construction, efficient in operation and which can be manufactured on a commercial scale, or in other words which is not so difficult to produce as to be beyond the 20 reasonable cost of such an article.

Another object of the invention is to provide a holder for nursing bottles which can be readily adjusted as to its width, height and position.

25 With these and other objects in view, which will more fully appear as the nature of the invention is better understood, the same consists in the combination, arrangement and construction of parts hereinafter 30 fully described, pointed out in the appended claims and illustrated in the accompanying drawings, it being understood that many changes may be made in the size and proportion of the several parts and minor details 35 of construction within the scope of the appended claims without departing from the spirit or sacrificing any of the advantages of the invention.

One of the many possible embodiments of 40 the invention is illustrated in the accompanying drawings, in which:—

Figure 1 is a vertical longitudinal section taken through a baby-carriage with the nursing bottle-holder in position thereon; Fig. 2 45 is a transverse section taken through the carriage showing a front elevation of the attachment; Fig. 3 is a side elevation of one of the bottle holding jaws; Fig. 4 is a front elevation of the means shown in Fig. 3; Fig. 5 is a plan view thereof; and Fig. 6 is a section taken on line 6—6 of Fig. 2.

In the drawings, the numeral 10 indicates 50 a baby carriage of any suitable construction. The attachment comprises a frame 11 sub- 55 stantially in the form of an inverted U,

which is held upon the sides of the body of the carriage by clamps 12, 12. More particularly the stationary jaws 13 of the clamps are made in the form of strips, which are held by means of movable jaws 14, 14 upon the inner faces of the sides of the carriage body, and to the stationary jaws are attached some distance above the upper edge of the carriage body upwardly extending vertical bars 15, 15, preferably by means of 60 screw bolts 16, 16 in mesh with wing nuts 17, 17. The upper ends of the bars 15 are connected by a cross member 18, which consists, preferably, of two telescoping sections 19 and 20, the section 19 being attached to 65 one of the bars 15, and the section 20 to the other one. The width of the frame 11 can thus be easily changed to fit carriages of varying sizes. From the section 19 of the cross member depends a supporting bar 21, 70 75 which is provided with an eye 22, fitting the section 19 of the cross member and held in place thereon by means of a thumb screw 23. The lower end of the supporting bar 21 is provided with a longitudinal slot 24, which is engaged by a screw bolt 25, the latter engaging also a depending arm 26. The threads of the screw bolt 25 mesh with a wing nut 27, bearing against the arm 26. By reason of the slot 24 the 80 relative positions of the supporting bar 21 and the arm 26 may be changed, and so also the angle of inclination of the arm 26 to the bar 21. To the lower end of the arm 26 is secured by means of a screw bolt 28 a bottle 85 holding jaw 29, the inner concave face of which is provided with a lining 30, preferably of felt. A second bottle holding jaw 30' is shiftably arranged upon the bolt 28. This jaw is also provided with a felt lining 90 and will, in coöperation with the jaw 29, clasp the nursing bottle 31 when the wing nut 32 is screwed up properly upon the bolt 28.

In use, the clamps 12 are fastened to the 100 sides of the baby-carriage, whereby the telescoping sections 19 and 20 of the cross member 18 will automatically adjust themselves to the width of the carriage. The supporting bar 21 is then shifted upon the section 19 105 of the cross member to the desired place, the arm 26 raised or lowered and placed at the desired angle to the supporting bar 21, and the wing nut 27 meshing with the bolt 25 tightly screwed up to hold the arm 26 in its 110

proper position. The bottle 31 is then inserted between the jaws 29 and 30' and secured in place.

If not needed, the frame 11 and the bottle support may be tilted forward around the bolts 16 into the body of the carriage.

What I claim is:—

1. In a nursing bottle-holder, the combination with two clamps adapted to be attached to the sides of a baby carriage, of a frame comprising two upwardly extending bars pivotally fastened to said two jaws and connected at their upper ends by a cross member, a supporting bar depending from said cross member, said supporting bar being shiftably arranged upon said cross member and provided at its lower end with a longitudinal slot, an arm provided upon its upper end with an aperture, a screw threaded bolt passing through said aperture and said longitudinal slot meshing with a nut, whereby the relative positions of said supporting bar and said arm may be changed and so also the angle of inclination of said arm to said bar, and bottle-holding jaws carried by said arm, said frame and the parts carried thereby being adapted to be tilted forward into the body of the carriage around the pivots which connect it with said clamps.
2. In a nursing bottle-holder, the combination with two clamps adapted to be attached to the sides of a baby carriage, of a frame comprising two upwardly extending bars pivotally fastened to said two jaws and connected at their upper ends by a cross member, a supporting bar depending from said cross member, said supporting bar being shiftably arranged upon said cross member, an arm, means for adjustably connecting said arm with said supporting bar both as to angular position and height, and bottle-holding jaws carried by said arm, said frame and the parts carried thereby being adapted to be tilted forward into the body of the carriage around the pivots which connect it with said clamps.

Signed at New York, in the county of New York and State of New York, this 7th day of March, A. D. 1912.

ELENORA NEUMANN.
